(57) **CLAIM**

I claim the ornamental design of a book clip with design attachment, as shown and described.

DESCRIPTION

FIG. 1 is a front elevational view of a book clip with design attachment, showing my new design;

FIG. 2 is a rear elevational view thereof;

FIG. 3 is a right side elevational view thereof, the left side view being a mirror image;

FIG. 4 is a perspective view thereof;

FIG. 5 is a top plan view thereof;

FIG. 6 is a bottom plan view thereof; and,

FIG. 7 is a view of the book clip with design attachment in a book. The book is shown in broken lines for illustrative purposes only and forms no part of the claimed design.
